Patented Feb. 14, 1956

176,923

CONDIMENT DISPENSER

Harold J. Marshall, Portland, Oreg.

Application April 4, 1955, Serial No. 35,340

Term of patent 14 years

(Cl. D44—22)

FIG. 1

FIG. 2

Fig. 1 is a side elevational view of the condiment dispenser of the design;

Fig. 2 is an elevational view rotated 90 degrees about its vertical axis with respect to the portion shown in Fig. 1; and

Fig. 3 is a top plan view thereof.

I claim:

The ornamental design for a condiment dispenser, as shown.
